(57) **CLAIM**

The ornamental design for a training and rehab apparatus as shown and described.

DESCRIPTION

FIG. 1 is a perspective view of a training and rehab apparatus, showing our new design.

FIG. 2 is left side elevational view thereof.

FIG. 3 is a right side elevational view thereof.

FIG. 4 is a left side elevational view thereof showing a roller element of the training and rehab apparatus in a first alternative position.

FIG. 5 is a left side elevational view thereof showing the roller element of the training and rehab apparatus in a second alternative position.

FIG. 6 is a front elevational view thereof.

FIG. 7 is a rear end elevational view thereof.

FIG. 8 is a top view thereof; and,

FIG. 9 is a bottom view thereof.

The broken line portions of the drawings show portions of the article that form no part of the claimed design. The broken line human figure in FIG. 1 is for the sake of showing the claimed training and rehab apparatus in a state of use and also forms no part of the claimed design.

1 Claim, 9 Drawing Sheets
